UNITED STATES PATENT OFFICE.

PAUL F. SHIVERS, OF LUDINGTON, MICHIGAN, AND JOHN F. LINDBERG, OF CHICAGO, ILLINOIS, ASSIGNEES OF ONE-HALF TO LEDDRA W. HOLT, OF LUDINGTON, MICHIGAN.

GOVERNOR FOR INTERNAL-COMBUSTION ENGINES.

Application filed November 12, 1919. Serial No. 337,579.

To all whom it may concern:

Be it known that we, PAUL F. SHIVERS, residing at Ludington, in the county of Mason and State of Michigan, and JOHN F.

5 LINDBERG, residing at Chicago, in the county of Cook and State of Illinois, citizens of the United States, have invented certain new and useful Improvements in Governors for Internal-Combustion Engines; and we do 10 hereby declare that the following is a full, clear, and exact description of the invention, such as will enable others skilled in the art to which it appertains to make and use the same.

15 This invention relates to governors for internal-combustion engines and has for its main object to provide means whereby starting of the engine is easily and quickly accomplished and whereby racing of the 20 engine due to sudden load reduction or failure of any element entering into the speed government of the engine will effect reduction in speed thereof.

The invention is particularly adapted to 25 so-called electric lighting and power plants of the type adapted for isolated locations, such as farms, small towns, hotels, resort cottages and vehicles, and which are actuated by internal combustion engines and more 30 particularly to that type of plant known as automatic or self-starting upon closure of the electric circuit through any of the translating devices interposed therein.

A further object of the invention in its 35 adaptation to such generating plants is to provide an automatic governor or control which will effect slowing down of the engine to prevent injury to the electric generating elements and circuits or the translating devices interposed therein in the event of any 40 accident such as the opening of the circuit controlling the governor or failure thereof for other causes, the breaking or failure of the spring associated with the governor or 45 control, or a sudden decrease in load on the engine or generator.

The invention consists in the combination or association of parts or elements herein-after fully described and claimed. A suitable or exemplary embodiment whereof is 50 illustrated in the accompanying drawings in which:

Figure 1 is a view in elevation, partly in

section, of an electric control or governor of the character and purpose set forth. 55

Figure 2 is a longitudinal section of the same on the line 2—2 of Figure 1.

Figure 3 is a longitudinal section, partly in section of the carburetor, Fig. 4 is a modification illustrating the adaptation of a ball 60 type of governor, and Fig. 5 a view of a hydrocarbon engine and generator and solenoid of the governor illustrating in conventional form the relation of the solenoid to the circuit of the generator. 65

The device comprises the carburetor 1 which, in the instance illustrated, consists of a tube or air passageway 2 into which the hydro-carbon feed nozzle 3 projects. The nozzle is adapted to be connected by means 70 of the pipe 4 with the source of a supply of hydro-carbon, and the supply of the hydro-carbon is controlled by a needle valve 5 in the usual manner. A shaft 6 carries the throttle valve 7 which is shown substantially 75 closing the air passageway. A passage 8 leads from the nozzle to the interior of the air passageway between the throttle valve 7 and the discharge or engine intake end of the air passageway. Mounted at one end 80 of the shaft 6 is a spur pinion 9 which projects into the housing 10 of the reciprocable plunger 11 constituting the armature of the solenoid 12. Said plunger 11 is equipped between its ends with a rack 13 meshing 85 with the spur pinion 9 for rotating the same in an obvious manner. The plunger or armature 11 is normally supported at the upper or outer limit of its movement with respect to the solenoid 12 by means of the 90 adjustable tension spring 14, depending upon whether the device is vertically or horizontally disposed.

Any of the many types and constructions 95 of carburetors for internal combustion engines purchasable on the market may be substituted for the one shown and described, it being essential only that the carburetor employed shall be equipped with a full jet located between the throttle or choke-valve 100 and the engine for reasons hereinafter fully explained.

The solenoid 12 is properly connected in the circuit of the generator so that as current is generated by the latter the solenoid 105 will be energized and will cause the arma-

ture or plunger 11 to be drawn down a distance depending upon the current value generated. In Fig. 5 we have illustrated the engine and generator and the solenoid in conventional form, the generator G being direct connected to the engine E and the solenoid 12 being connected across the two circuit wires W leading from the generator. Normally when the plunger 11 is at the upper limit of its movement the throttle valve is closed or substantially closed as shown in Figure 1, so that only a very limited air intake opening is presented, so that upon starting the internal combustion engine for driving the generator a relatively rich starting mixture of carbureted air will be introduced into the engine to start the same. As is well known in automobile practice and wherever internal combustion engines are employed, the latter are more quickly and readily started by the introduction of a relatively rich carbureted air initially. As soon as the engine is started the generator actuated thereby will deliver current to the solenoid 12 whereupon the latter will draw down the plunger or armature 11 a distance depending upon the current value generated and the choke valve will be moved toward open position thus enlarging the air intake and causing an increase in engine speed and a proportionate increase in current until the current generated attains its predetermined voltage. If the load on the generator is at this time its maximum, then the choke valve will retain its approximately maximum opening but as the current consumption decreases due to turning out lights or shutting off other translating means interposed in the generator circuit the load on the engine will decrease without, however, decreasing the voltage of the generated current. This will obviously result in an increase in engine speed and a consequent increase in voltage of the generated current thus causing the armature 11 to be moved still farther against the action of the spring 14 thus causing the choke valve of the carburetor to turn beyond the wide open position and effecting a partial choking of the air intake and a decrease in engine speed substantially of such intake. The winding of the solenoid and the tension of the spring 14 are such that if the maximum voltage to be generated is, for example, 110 and it should rise to 115, the armature 11 will respond to such extent as to move the choke valve to a substantially closed position to prevent all possibility of continuation of engine speed or increase thereof to effect generation of current to exceed a safe limit of 115 volts.

If, for example, the spring 14 should break or be too weak to offer the requisite resistance to the movement of the armature 15 in response to current increases, the result

would be that the engine would never attain the desired maximum speed, and in the event that the supply of current to the solenoid should, for any reason, such as a short circuit or the breaking or loosening of a feed wire to same, the spring 14 would either retain the armature at or return it instantly to its normal position thus holding or returning the choke valve at or to its initial position. In lighting plants of the character referred to the starting of the internal combustion engine is effected by an electric motor deriving its energy from a storage battery and, in order that the latter may not be exhausted by an excessive duration of the cranking operation, to the end that the life of the storage battery may be increased as far as possible and, further, so that the normal desired current value may be generated as soon as possible after closing the circuit through a translating device, it is, of course, desirable that starting of the engine and generation of power should be almost instantaneous and this is best accomplished by almost completely choking the air intake to the carburetor initially to insure the feed of rich carbureted air to the engine. This advantage of the device is supplemented by the other advantages hereinbefore set forth thus making the device not only advantageous with respect to its several functions and the manner in which they are performed but also with respect to the simplicity and cheapness of its construction.

It will be apparent, of course, that the device is equally applicable to electric light and power plants of the several types on the market regardless of the voltage of the current generated.

Our said device is particularly adapted for such plants as are, for example, illustrated and described in the application for Letters Patent of Scott J. Matthews, filed March 7th, 1917, Serial No. 153,015, and in Letters Patent to L. B. Jones, No. 1,081,749, dated December 16th, 1913; F. M. Slough, No. 1,192,006, dated July 25th, 1916; and many others; in fact wherever the prime mover is started by a battery actuated motor or motor generator or by means of a pneumatic motor fed from a limited supply of compressed air as in the patent to C. D. Knight et al., No. 1,028,364 dated June 4th, 1912.

The essential and most important and advantageous feature of the invention resides in the employment of a carburetor having a throttle or choke-valve disposed in the above described relation to the fuel nozzle and engine and so associated with means responsive either directly or indirectly to the engine speed as to be normally disposed at one closed or substantially closed position and adapted to turn toward and to its

other closed position in response to increase in engine speed thus adapting it to any very simple type of governor whether electrical or mechanical, the electrical type 5 shown and described being very advantageous in some particulars, and, therefore preferable. The initial or normal position of the choke or throttle-valve insures quick starting of the engine and affords the most 10 advantageous and economical means of preventing racing of the engine under the several specific conditions, or their equivalents, above set forth.

In Figure 4, we have shown a simple 15 mechanical governor of the ball type in which sleeve 15 will be suitably connected to the engine to be rotated thereby. Balls 17 are suitably connected to the sleeve and to rod 16 suitably connected to rack rod 18 which 20 meshes with pinion 19 on shaft 20, the pinion and shaft being identical with pinion 9 and shaft 6. As the speed of the engine increases for any reason, the balls will travel outwardly in the usual manner causing rod 25 16 to descend in sleeve 15 and move the rack rod upwardly to move the valve as before described.

Thus it will be understood that while we have shown and described an exemplary 30 and preferred embodiment of the invention herein, the same may be otherwise embodied to adapt it to the characteristics of all types of generating sets or plants of the character aforesaid or any type of internal combustion 35 engine without departing from the invention as defined in the appended claims.

What we claim is:

1. A governor for internal combustion engine-driven electric generating plants comprising a carburetor adapted to be connected 40 to the engine and having an air passageway therein, a valve within the air passageway adapted to be turned continuously in one direction from substantially closed position 45 to wide open position and again to substan-

tially closed position, means normally maintaining the valve in substantially closed position and means to turn the valve in the aforesaid direction, the latter means being responsive to the voltage of the electric 50 current generated by the generator.

2. A governor for internal combustion engine-driven electric generating plants comprising a carburetor adapted to be connected to the engine and having an air 55 passageway therein, a valve within the air passageway adapted to be turned continuously in one direction from substantially closed position to wide open position and again to substantially closed position, the 60 carburetor having a fuel jet communicating with said air passageway between said valve and the engine, and means to turn the valve in the aforesaid direction, said means being responsive to the voltage of the current 65 generated by the electric generating means.

3. A governor for internal combustion engine-driven electric generating plants comprising a carburetor adapted to be connected to the engine and having an air passageway therein, a valve within the air passageway adapted to be turned continuously 70 in one direction from substantially closed position to wide open position and again to substantially closed position, the carburetor 75 having a fuel jet communicating with said air passageway between said valve and the engine, a rack carrying plunger adapted to turn the valve in the aforesaid direction, voltage responsive means connected in the 80 circuit of the electric generating means for moving the plunger in one direction and means to move the plunger in the opposite direction for normally maintaining the valve in substantially closed position.

In witness whereof, we have hereunto signed our names this 4th day of November, 1919.

PAUL F. SHIVERS,
JOHN F. LINDBERG.
